UNITED STATES PATENT OFFICE

HUBERT C. HART, OF UNIONVILLE, CONNECTICUT

SAFETY RAZOR

Application filed March 28, 1930. Serial No. 439,699.

The invention aims to provide a construction which is generally improved over that shown by U. S. patent to Finney, No. 1,051,094 of January 21, 1913, of which patent I am assignee. The improved construction hereinafter described, provides a razor which may be more advantageously manufactured and one having a more efficient and durable form.

10 With the foregoing in view, the invention resides in the novel subject matter herein-after described and claimed, description being accomplished by reference to the accom-panying drawing.

15 Fig. 1 is a side elevation.

Fig. 2 is a central longitudinal sectional view.

Fig. 3 is a disassembled perspective view.

20 Fig. 4 is a plan view showing the two blanks from which the head of the razor is formed.

In the drawing above briefly described, the numeral 5 denotes a spring metal blank having widened ends, said blank being bent into 25 U-shape to provide a front plate 6 and a back plate 7. The free edge of the plate 7 is bent into channel form as shown at 8 and is pro-vided with a plurality of slots 9 extending across the channel, providing a guard comb, and said edge projects beyond the outer free 30 edge 10 of the front plate 6. A relatively heavy, stiff plate 11 is disposed at the rear side of the front plate 6 and at its inner edge is secured to said plate 6, by rivets or the like 12.

35 The free outer edge 13 of the plate 11 is dis-posed beyond the edge 10 of the front plate 6 and is spaced inwardly from the comb 8—9. This plate 11 is provided at the ends of its edge 13 with projecting, rearwardly turned fingers 14 to engage shoulders 15 at the ends of the comb, to limit the movement of the plates 6 and 11 toward the rear plate 7.

40 The plate 6 and the plate 11 are trans-versely bowed away from each other as seen at 16 and 17, respectively, for the purpose of receiving a head or back 18 on a blade 19. At one end of the bowed formation 16, a lug 20 (Fig. 4) is provided to limit insertion of the blade between the bowed parts of the plates 6 and 11, and the blade is held between these

plates by friction created by the resiliency of the plate 6.

For lightness, the bowed portion of the plate 11 is formed with openings 21 between its central and its end portions, and rigidly secured to said central portion, is a rearwardly projecting, polysided shank 22 which passes through an opening 23 in the rear plate 7, said shank being provided with a threaded rear end 24. A tubular handle 25 55 slidably but non-rotatably surrounds the shank 22 and abuts the rear plate 7, and a sleeve 26 is threaded upon the shank end 24 within the handle 25, said sleeve having a knurled knob or head 27 at its rear end. Ro-tation of this knob or head in one direction, 60 causes rearward movement of the shank 22 to pull the plate 11 and the front plate 6 rear-wardly to dispose the edge of the blade 19 in proper relation with the comb 8—9, for 65 shaving. During this operation (rearwardly pulling the plates 6 and 11), there will be no distortion of said plates, due to the rigi-dity of the plate 11, and hence there is no 70 danger of warping the blade with liability 75 of poor shaving results. When the knob or the like 27 is rotated in the other direction, shank 22 moves forwardly under the resi-liency of the blank 5, the plates 6 and 7 then 80 occupying positions considerably in advance 85 of the rear plate 7, allowing easy cleaning, as will be clear from Fig. 3.

The details disclosed have proven desir-able from all standpoints and hence are pre-ferrably followed, but within the scope of the 85 invention as claimed, minor variations may be made.

I claim:

A safety razor comprising a spring metal blank bent into U-shape and having widened 90 end portions forming a front plate and a rear plate, the free edge of said rear plate being bent into channel form and slotted trans-versely of the channel to provide a guard comb, a relatively stiff plate at the rear side 95 of said front plate and having its outer edge disposed beyond the outer edge of said front plate but spaced inwardly from said comb, said outer edge of said stiff plate being pro-vided at its ends with projecting rearwardly 100

turned fingers adapted to lie upon the ends of said comb, means securing the inner edge portions of said front plate and said stiff plate together, whereby the former may act to clamp a blade against the latter, said front plate and said stiff plate being transversely bowed away from each other to hold the head of the blade, and a combined handle and adjuster for drawing said front and stiff plates toward said rear plate, said combined handle and adjuster having a portion abutting said rear plate, and a portion connected with said stiff plate, said rear plate having an opening through which the last-named portion passes.

15 In testimony whereof I have hereunto affixed my signature.

HUBERT C. HART.
